(57) **CLAIM**

The ornamental design for a handle for a household implement, as shown, and described.

DESCRIPTION

FIG. 1 is a perspective view of a handle for a household implement;

FIG. 2 is a front view thereof;

FIG. 3 is a rear view thereof;

FIG. 4 is a right elevation view thereof, the left elevation view being a mirror image thereof;

FIG. 5 is a top plan view thereof; and,

FIG. 6 is a bottom plan view thereof.

The broken lines are for the purpose of illustrating portions of the article that form no part of the claim.
